UNITED STATES PATENT OFFICE.

WILLIAM F. BROEKER, OF BEARDSTOWN, ILLINOIS.

LUBRICATOR.

1,000,232.

Specification of Letters Patent.

Patented Aug. 8, 1911.

Application filed June 8, 1910. Serial No. 565,898.

To all whom it may concern:

Be it known that I, WILLIAM F. BROEKER, a citizen of the United States, residing at Beardstown, in the county of Cass and State 5 of Illinois, have invented a new and useful Lubricator; and I do hereby declare the following to be a full, clear, and exact description of the invention, such as will enable others skilled in the art to which it 10 appertains to make and use the same.

This invention relates to an improvement in lubricators, and has for its principal object to provide a novel means for preventing the loss of plugs for lubricator cups, such 15 as are commonly employed in connection with driving rods of locomotives, and with other machinery.

Another principal object of the invention is to provide a locking means for plugs of 20 the class described, which will permit of the plug being easily adjusted or removed without any delay or inconvenience.

A still further object of the invention is to provide a closure for the lubricator, 25 whereby the lubricant will be prevented from escaping, due to the vibrations of the machine to which the lubricator is attached.

With these and other objects in view, the invention consists in the construction and 30 novel combination of parts hereinafter fully described, illustrated in the accompanying drawing, and pointed out in the claim here- to appended; it being understood that various changes in the form, proportion, size 35 and minor details of construction, within the scope of the claim, may be resorted to without departing from the spirit or sacrificing any of the advantages of the invention.

40 In the drawing:—Figure 1 is a side elevation of a grease cup, showing my improvement associated therewith. Fig. 2 is a vertical sectional view through the same, parts thereof being shown in elevation. Fig. 3 is 45 a sectional view of the closure, and Fig. 4 is a top plan view of the same.

Like reference numerals designate corresponding parts in all the figures of the drawing.

50 Referring to the drawing, 1 designates a cup which is provided with exterior threads 2, interior threads 3 and an angular head 4, said head being adapted to be engaged by a wrench or other suitable tool, by means of 55 which the said cup can be secured in a bearing or lubricating box. The head 4 of the

cup is provided on its upper face with oppositely disposed and preferably concaved depressions 5. Arranged to engage the interior threads 3 of the cup is a piston head 60 having an upwardly extending angular stem 11. A transverse pin 14 is inserted through a corresponding opening in the larger end of the stem and forms a stop for a washer 13.

65 The invention further comprises a closure 7, which is provided with an angular opening 10, adapted to receive the stem 11. This closure is preferably formed of flat metal and normally rests above the piston upon 70 the top face of the head 4 of the cup. This closure is provided with an upwardly extending peripheral flange 8 and the said closure has a diameter substantially equal to the diameter of the cup. The closure is 75 furthermore provided with oppositely disposed depending lugs 6, which are formed by depressing the flange 8 by any suitable tool. These lugs are adapted to be seated within the depressions 5 of the head 4 to 80 prevent any rotary movement of the said closure.

85 Interposed between the washer 13 and the closure 8 is a coiled spring 9 of conical construction, the upper or smaller end thereof bearing against the washer, and the lower or larger end bearing upon the closure.

From the foregoing, it will be seen that, 90 by reason of the fact that the lower end of the coiled spring is larger, greater pressure is exerted upon the washer and thereby any lubricant is prevented from escaping.

When it is desired to lower the piston head, the stem 11 is turned and, as its operation takes place, the tension of the coiled 95 spring is increased. Therefore it will be observed that the farther the piston is inserted in the cup, the greater pressure will be exerted upon the closure.

What I claim is:

100 In combination with a grease cup having its upper face provided with oppositely arranged depressions, of a piston mounted therein for vertical adjustment and including a stem rectangular in cross section extending upwardly from the piston, a closure fitted down over the stem in engagement with the upper surface of the cup and provided with a peripheral flange and including oppositely arranged lugs pressed out of 105 the flange to engage the depressions of the cup, a pin extending transversely of the

stem adjacent its upper end, a washer on the stem below the pin, and a spring interposed between the closure and the washer to hold the lugs and depressions in coöperation thereby preventing rotary movement of the closure, the spring having its lower portion arranged within the peripheral flange to prevent displacement of the spring.

In testimony whereof I have signed my name to this specification in the presence of ¹⁰ two subscribing witnesses.

WILLIAM F. BROEKER.
